[57] CLAIM

The ornamental design for a hand-held pneumatic control device, as shown and described.

DESCRIPTION

FIG. 1 is a perspective view of one embodiment of a hand-held pneumatic control device embodying our new design;

FIG. 2 is a top plan view of the hand-held pneumatic control device depicted in FIG. 1;

FIG. 3 is a left side elevational view of the hand-held pneumatic control device depicted in FIG. 1;

FIG. 4 is a front side elevational view of the hand-held pneumatic control device depicted in FIG. 1, the back side elevational view being a mirror image thereof;

FIG. 5 is a right side elevational view of the hand-held pneumatic control device depicted in FIG. 1; and,

FIG. 6 is a bottom plan view of the hand-held pneumatic control device depicted in FIG. 1.
